ALLAN A. JOHNSON, OF NATIC, RHODE ISLAND, ASSIGNOR TO KIP-ARMSTRONG COMPANY, OF NEW YORK, N. Y., A CORPORATION OF NEW YORK.

WARP STOP-MOTION FOR LOOMS.

SPECIFICATION forming part of Letters Patent No. 778,132, dated December 20, 1904.

Application filed April 4, 1904. Serial No. 201,518.

To all whom it may concern:

Be it known that I, ALLAN A. JOHNSON, a citizen of the United States, and a resident of Natic, in the State of Rhode Island, have invented certain new and useful Improvements in Warp Stop-Motions for Looms, of which the following is a specification.

The present invention relates to warp stop-motions for looms, and more particularly to the mechanism for releasing the shipper-lever, and will be understood by reference to the accompanying drawings, in which—

Figure 1 is a side elevation of a loom, showing the application of the invention thereto; Fig. 2, a front elevation of the left-hand end of the breast-beam; Fig. 3, a perspective detail view, and Fig. 4 a detail view of a modification.

Similar reference-numerals indicate similar parts in the several views.

Referring to the drawings, 1 designates the frame of the loom; 2, the lay; 3, the breast-beam; 4, the shipper-lever; 5, the warps; 6, the warp-beam; 7, the reed, and 8 the heddles. These parts may be and are of the usual construction and arrangement in looms. The shipper-lever, as usual, occupies a slot 9 in a bracket 10, forming an extension of the breast-beam, and engages, when the loom is running, a shoulder 11. When freed from this shoulder, a spring (not shown) shifts the shipper-lever to stop the loom. In order to set the shipper-lever free, an electromagnet 12 is mounted below the breast-beam on a bracket 13, secured by suitable means to the loom-frame, and its armature-lever 14 is connected by a link or wire rod 15 to one end of a dagger 16. Pivotaly supported by pins or studs 17 in a bracket 18, secured to the loom-frame, is a knock-off lever 19, attached at its lower end to the dagger 16 and its upper end adapted to engage the shipper-lever 4. When the magnet 12 is energized, the dagger 16 is moved into such position as to be impinged upon by a bunter 20, mounted on the lay or some other vibrating or moving part of the loom. The impingement of the bunter on

the dagger moves the knock-off lever to free the shipper-lever, as will be readily understood, and permits the latter to act to stop the loom.

In order to energize the electromagnet 12, and thus set in motion the loom-stopping devices whenever a warp-thread breaks or becomes unduly slack, a controlling-circuit 21 is employed. This circuit includes the coils of said magnet and a generator, and it has its terminals and circuit-closing devices situated at the point 22. It may be stated here that in this general class of stop-motions a thin metallic drop is suspended from each warp-thread, and these drops slidably embrace a bar called a "compound terminal." This compound terminal consists of a bar-terminal of the controlling-circuit, and with it the drops are at all times or normally in contact, and of a metal strip forming the other terminal of the controlling-circuit and set in, but insulated from the other or bar terminal. When the warp-thread breaks or becomes unduly slack, the drop suspended thereon falls and closes the controlling-circuit through the electromagnet. The circuit 21 also includes a switch 23 of any usual or well-known type, having contact-plates by which the circuit may be opened or closed. As here shown, the switch is supported upon a bracket 13' and is provided with a switch-lever 24 in contact with and adapted to be moved by a projecting arm 25, secured to the shipper-lever, said arm being forked or otherwise connected, so as to move said lever in both directions. During the normal operation of the loom the circuit is closed through the switch and at all other points except through the compound terminal at 22. When the circuit is closed at 22, the shipper-lever is released, as above described, to stop the loom, and as said lever is shifted the switch-lever 24 is moved, so as to immediately, after the loom has been stopped, break the circuit through switch 23. The circuit is therefore closed solely for the purpose of shifting the shipper-lever, and when that work has been done the circuit is broken.

When the loom is again set in motion, the break in the circuit at the switch 23 will be closed.

In looms of this character the bunter for impinging upon the dagger has usually been a solid projecting block or finger which did not provide a very wide range of action, and in practice it has been found that a slight bending or displacement of the link or wire rod 15 and the consequent displacement of the dagger from its normal position, whether intentional or accidental, results in the dagger being held out of the path of the bunter when the electromagnet is energized upon the breaking or undue slackening of a warp-thread. Consequently the loom is not knocked off, and the cloth is imperfect. To overcome the objections incident to the ordinarily-used form of bunter, I have devised one whereby any deviation of the dagger from its normal position when the loom is running will cause it to be impinged upon by the bunter, resulting immediately in shifting the shipper-lever to stop the loom.

25 One embodiment of my invention is illustrated in Fig. 3, in which the bunter 20 is formed with a base, by which it may be attached to the lay or other moving part of the loom, and a projecting body portion having 30 side walls 26 and face 27. The bunter is preferably formed of a casting and is recessed through the face at 28 a sufficient depth to permit the dagger 16 to pass freely into the same without impinging during the normal 35 running of the loom. When the electromagnet is energized, the dagger will be drawn out of the path of the recessed portion of the bunter and will be impinged upon by the face 27. If desired, the said face may be provided with 40 grooves 29 to prevent the dagger sliding on the face and to insure a good contact. It is obvious that any slight intentional bending of the link or wire rod 15, so as to cause the dagger to escape the recess 28, would result in 45 the knocking off of the loom, and any such bending sufficient to cause the dagger to escape the bunter altogether could easily be detected. Such detection in the forms of bunters commonly used is difficult, if not impossible. 50 I thus provide a means by which any unwarranted interference with the proper working of the stop-motion by the weaver is either prevented or its detection assured.

Fig. 4 shows a slightly-modified form of 55 bunter in that the casting may be made by omitting one of the side walls, the face 27, as in Fig. 3, being a sufficient distance from the base as to prevent impingement against the dagger during the running of the loom.

60 The dagger may be so positioned as to have its outer end either raised or lowered to bring it into the path of the face of the bunter when the electromagnet 12 is energized as described in United States Patent No. 713,836, dated

November 18, 1902, to W. H. Baker and Fred- 65 eric E. Kip; also, as described in that patent and in United States Patent No. 741,951, dated October 20, 1903, to the same parties, the dagger 16, armature-lever 14, and their connecting parts may be nearly balanced and actuated by gravity to put the parts in their normal or inoperative positions. If desired, however, springs may be employed to restore the parts to their normal positions when the electromagnet 12 is deenergized; also, the switch- 70 lever 24 may be provided with a spring to restore it to its normal position when the loom is started by moving the shipper-lever into engagement with shoulder 11. 75

As shown in Fig. 2, the brackets 13 and 13' 80 for supporting the magnet and switch, respectively, are cast in a single piece and bolted to the loom-frame. The dagger 16 may also be mounted on a portion of the same casting, and by so doing these parts may be applied 85 to the loom complete.

Being the first to employ in a warp stop-motion a device which prevents the operative from interfering with the effectiveness of the knocking-off device, I desire to claim the same 90 broadly without reference to the special means for accomplishing the result. It is also understood that the device is adapted to a mechanical as well as to an electrical warp stop-motion.

What I claim, and desire to secure by Letters Patent, is—

1. A stop-motion for looms comprising a dagger, a bunter having a recess of sufficient depth to permit said dagger to enter freely 100 therein when the dagger is in its normal position, and an impinging face to cause the loom to knock off when the dagger is moved from its normal position.

2. A stop-motion for looms comprising a 105 dagger, and a bunter having a recess of sufficient depth to permit said dagger to enter freely therein when the dagger is in its normal position, and an impinging face whereby a slight displacement of the dagger from its 110 normal position will cause the loom to knock off and also whereby any displacement of the dagger to escape the bunter may be readily detected.

3. A bunter for use on looms having a body 115 portion with a recess of sufficient depth to permit a dagger to enter freely therein when the dagger is in its normal position, and an impinging face whereby the loom will knock off upon any slight displacement of the dagger from its normal position and whereby any unusual displacement may be readily detected.

4. A stop-motion for looms comprising a dagger, an electric circuit including a magnet, an armature therefor, a link connecting said armature and dagger, a bunter on a moving part of the loom, said bunter having a recess of sufficient depth to permit said dagger to

enter freely therein when the parts are in their normal positions, and an impinging face whereby a displacement or breaking of said link and the consequent displacement of the 5 dagger from its normal position will result in knocking off the loom or make possible the detection of such distortion or breaking.

5. A warp stop-motion for looms comprising drop devices maintained in normal position by warp-threads, electric circuits having terminals adapted to be closed by said drop devices upon the breakage or undue slackness of a warp-thread, a dagger, a protective knock-off device for preventing the operative 15 from wilfully displacing the dagger to thereby allow the loom to run consisting of a bunter having a body portion with a recess of sufficient depth to permit the dagger to enter therein during the normal running of the 20 loom and an impinging face, and means when said circuit is closed for moving the dagger into position to strike the impinging face of the bunter to thereby stop the loom.

6. A bunter for use on looms having a body 25 portion with a recess of sufficient depth to permit a dagger to enter freely therein when the dagger is in its normal position, and a surrounding impinging face.

7. A bunter for use on looms having a body 30 portion with a recess of sufficient depth to permit a dagger to enter freely therein when the dagger is in its normal position, and a grooved surrounding impinging face.

8. A bunter for use on looms having a body 35 portion with a substantially central recess therein of a depth sufficient to permit a dagger to enter freely therein when the dagger

is in its normal position, and a surrounding impinging face.

9. The combination with a warp stop mechanism for looms, of a shipper-lever and means to release the same to stop the loom comprising a dagger, means connecting said shipper-lever and dagger, a bunter on a moving part of the loom, said bunter having a body portion with a recess of sufficient depth to permit said dagger to enter freely into said recess when the dagger is in its normal position and a surrounding impinging face, and means to move said dagger into the path of the impinging face of the bunter upon the breakage or undue slackness of a warp-thread.

10. The combination in a warp stop mechanism for looms, of a shipper-lever and means to release the same to stop the loom comprising a dagger, a knock-off lever secured to said dagger and adapted to engage said shipper-lever, a bunter on a moving part of the loom, said bunter having a body portion with a recess of sufficient depth to permit said dagger to enter freely into said recess when the dagger is in its normal position and a surrounding impinging face, and means to move said dagger into the path of the impinging face of the bunter upon the breakage or undue slackness of a warp-thread.

In witness whereof I have hereunto signed my name in the presence of two subscribing witnesses.

ALLAN A. JOHNSON.
